UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

METHOD OF MANUFACTURING MULTIPLE-CONTACT STRIPS.

1,287,101.

Specification of Letters Patent. Patented Dec. 10, 1918.

Application filed August 1, 1917. Serial No. 183,999.

To all whom it may concern:

Be it known that I, JOHN NEWBERRY REYNOLDS, a citizen of the United States, residing at Greenwich, in the county of Fairfield 5 and State of Connecticut, have invented certain new and useful Improvements in Methods of Manufacturing Multiple-Contact Strips, of which the following is a full, clear, concise, and exact description.

10 This invention relates to the process of manufacturing multiple contact strips, each of which is composed of a plurality of longitudinally extending bare conductors which are divided into sets, each wire being provided with a plurality of longitudinally separated contact surfaces, the different wires comprising a set having their contact surfaces longitudinally separated from each other, while the corresponding wires of separate sets have their contact surfaces in the same line transversely of the strip.

15 The object of this invention in general is to provide for the manufacture, in an efficient and economical manner, of a type of multiple contact strip outlined in the foregoing paragraph.

20 The process of this invention consists in general in forming a web consisting of bare conductors with insulating strips inserted therebetween to displace portions of the conductors relative to the normal plane thereof and at longitudinally separated positions. The web so formed is clamped upon a mounting plate previously prepared with insulating compound and the conductors are fanned out at one end of the mounting plate and bent back upon themselves to form connecting terminals. In the final step of the process, the mounting strip with the web thereon 25 is heat treated or baked to set said web in the insulating compound.

25 In the drawings illustrating this invention, Figures 1, 2, 3, 4, 5, 6, 7 and 8 are views illustrating the successive steps and apparatus entering into the process; and Fig. 9 is a fragmentary view of the finished product.

30 In the first step of the process of this invention a plurality of wires 7, 7, 8, 8 and 9, 9 (Fig. 1) are clamped at one end to a plate 10, over which they extend longitudinally and are placed under tension by suitable means such as weights 11, 11. The face of the plate 10 over which the wires 7, 7,

8, 8 and 9, 9 extend is provided between its ends with a plurality of equally spaced transversely extending depressions 12, 12. A presser roller 13 is provided on its face with a plurality of circumferentially arranged projections 14, 14 adapted as said roller 13 is moved over the plate 10 to depress two out of each three wires into the depressions 12, 12 of said plate. The projections 14, 14 of the presser roller 13 are arranged in pairs, each pair having its projections circumferentially separated from each other to such a distance that they engage the wires upon which they act, at points near opposite sides of the depression 12 to permit of the insertion of an insulating strip 15, 16 or 17, as the case may be. The insulating strips 15, 16 and 17 are each provided with notches 20, 20 in their edges adapted to be engaged by the undepressed portion of one of the conductors 7, 7, 8, 8 or 9, 9. The notching of the several strips 15, 16 and 17 being such that when they are inserted between the wires, the wires 7, 7 will be in the notches of the strips 15, the wires 8, 8 in the notches of strips 16 and the wires 9, 9 in the notches of strips 17. For convenience these strips 15, 16 and 17 may be arranged in three piles in a magazine 21 and moved one by one into a hopper 22 by means of slides 23, 24 and 25. From the hopper 22 they may be separately inserted between the wires by means of a slide 26.

35 After the wires 7, 7, 8, 8 and 9, 9 have been stretched over the plate 10, the presser roller 13 is passed thereover from right to left. In its first position it will depress all of the wires 7, 7 and 9, 9 into the corresponding depression 12 in the plate 10 and an insulating strip 15 will be inserted between the relatively depressed wires. In the second position of the roller 13 all of the wires 7, 7 and 8, 8 will be depressed and an insulating strip 16 inserted between the relatively displaced wires, and in the third position of the roller 13 all of the wires 8, 8 and 9, 9 will be depressed, and an insulating strip 17 will be inserted between the relatively displaced wires. In its fourth position the roller 13 will have made a complete revolution and the operation above stated will be continued until the web of wires and insulating strips is of the length desired.

When the web has attained the desired length in the manner above described, a metal strip 30 which has been previously prepared with a heat hardenable insulating material is placed underneath the web and an insulating block 31 is clamped into place. A similar block is also used at the opposite end. A comb 32 (Figs. 3 to 6) having diagonally extending slots 33, 33 therein is brought up under the wires so that the slots 33, 33 separate the wires sufficiently to permit them to engage slots 34, 34 in a steel block 35 (Fig. 3). The comb 32 is then lowered (Fig. 4) until the wires between it and the steel block 35 are parallel with each other. A terminal forming steel block 36 (Figs. 5, 6, 7 and 8) is then secured in place above the wires, and an insulating block 37 is set into place beneath the wires and beyond the position of the terminal forming steel block. The insulating block 37 is then carried over the terminal forming block 36 and into place, close up to the steel block 35 to loop the wires over the terminal forming block 36, the block 37 being inverted in the operation.

Clamping means comprising a clamping plate 40 (Figs. 7 and 8), which is placed over the insulating block 37, and screw clamps 41 and 42 are applied to secure the mounting strip 30 and the block 37 together temporarily. With these parts clamped together the steel block 35 and the terminal forming block 36 are removed and the comb 32 is lowered until the wires are drawn in beyond the end of the formed strip into their normal positions. A clamping block 45 is next applied to the wires beyond the formed strip and the wires are cut at 46. The formed strip is then placed in the oven and baked for the required period of time. After having been baked to set the web in the insulating material, the strip may be removed from the oven and the wire stubs, which were left when the cut was made at 46, may be cut off adjacent to the block 37.

While the process of this invention is shown and described in connection with a terminal strip adapted for three conductor circuits, it will be obvious to those skilled in the art to which this invention relates that the process of the invention may be applied to the manufacture of strips for circuits of any number of conductors.

55 What is claimed is:

1. The process of manufacturing a multiple contact strip for multiple conductor circuits which consists in arranging a number of bare wires, constituting a plurality of sets in the same plane, depressing all but one of the wires of each set below the normal plane of the wires at successive positions along the length of the wires and in such a manner that each wire of each set 60 will be depressed in consecutive positions

less in number by one than there are wires in a set and undepressed in one position between its depressed positions, inserting insulating strips between the relatively displaced wires, and securing the web thus 70 formed to a mounting plate.

2. The process of manufacturing a multiple contact strip for multiple conductor circuits which consists in arranging a number of bare wires, constituting a plurality of sets in the same plane, depressing all but one of the wires of each set below the normal plane of the wires at successive positions along the length of the wires and in such a manner that each wire of each set 80 will be depressed in consecutive positions less in number by one than there are wires in a set and undepressed in one position between its depressed positions, the undepressed portions of corresponding conductors of the separate sets being in the same relative position transversely of the plane of the wires, inserting insulating strips between the relatively displaced wires at each successive position of depression, and securing the web thus formed to a mounting plate.

3. The process of manufacturing a multiple contact strip which consists in rigidly clamping a plurality of bare conductors at 95 one end and placing said conductors under tension, displacing portions of said conductors relative to the common plane thereof, inserting insulating strips between said conductors at the displaced portions thereof, 100 and securing the web so formed by the bare conductors and insulating strips to a mounting plate.

4. The process of manufacturing a multiple contact strip which consists in rigidly 105 clamping a plurality of bare conductors at one end and placing said conductors under tension, displacing portions of adjacent conductors with respect to the common plane of the conductors in such manner that the un- 110 displaced portions of different conductors occur at positions longitudinally separated from each other, inserting insulating strips between said conductors to maintain the displacement of said displaced portions, and 115 securing the web so formed to a mounting plate.

5. The process of manufacturing a multiple contact strip which consists in rigidly 120 clamping a plurality of bare conductors at one end, placing said conductors under tension, displacing portions of said conductors, inserting insulating strips between said conductors at the displaced portions, securing the web so formed to a mounting plate, fanning out the conductors of the web at one end thereof, and bending them back upon themselves to form terminals.

6. The process of manufacturing a multiple contact strip which consists in rigidly 125

clamping a plurality of bare conductors at one end, placing said conductors under tension, inserting insulating strips between adjacent conductors to maintain them displaced relative to the same plane, clamping the web comprising the bare conductors and insulating strips to a mounting strip prepared with insulating compound, forming terminals in the conductors at one end of said web, and heat treating the web and plate to set said web in said insulating compound.

7. The process of manufacturing a multiple contact strip which consists in rigidly clamping a plurality of bare conductors at one end, placing said conductors under tension, inserting insulating strips between adjacent conductors to maintain them displaced relative to the same plane, clamping the web thus formed to a mounting plate prepared with insulating compound, fanning out the wires at one end of the web, and bending them back upon themselves to form terminals, and heat treating said mounting plate and web to set said web in said insulating compound.

8. The process of manufacturing a multiple contact terminal strip for three-wire circuits which consists in arranging a plurality of bare wires in the same plane, depressing two out of each three wires below the level of a third at successive positions along the length of the wires in such a manner that each wire of each three will be depressed in two consecutive positions and undepressed in a third position, inserting insulating strips between the depressed and undepressed conductors to maintain them in their relatively displaced positions, and securing the web thus formed by the insulating strips and bare conductors to a mounting plate.

9. The process of manufacturing a multiple contact terminal strip for three-wire circuits which consists in arranging a plurality of bare wires, equal to some multiple of three, in the same plane, depressing two wires of each set of three below the level of the third at successive positions along the length of the wires in such a manner that each wire of each three will be depressed in two consecutive positions and undepressed in a third position, corresponding wires of each set of three being undepressed in the same relative positions transversely of the

plane of the wires, inserting an insulating strip between relatively displaced wires at the consecutive points of depression, and securing the web of insulating strips and bare wires to a mounting plate.

60

10. The process of manufacturing a multiple contact member which consists in arranging a plurality of bare conductors in a plane, displacing portions of said conductors with respect to said plane, inserting insulating members between said conductors to maintain them displaced, and securing the structure thus formed to a mounting plate.

65

11. The process of manufacturing a multiple contact member which consists in securing a plurality of bare conductors at one end, disposing each of said conductors to form contact portions at successive positions along the length thereof, inserting insulating members between said conductors, securing the structure thus formed to a mounting plate prepared with insulating material, and heat treating said mounting plate and structure to set said structure in said insulating material.

70

75

80

12. The process of manufacturing a contact member which consists in arranging a plurality of bare conductors in a plane, placing said conductors under tension, displacing said conductors with respect to the common plane thereof at successive positions along their length, inserting insulating members between said conductors to maintain the same in displaced position, and securing the structure thus formed to a mounting plate.

85

13. The process of manufacturing a multiple contact strip which consists in arranging a plurality of bare conductors constituting a plurality of sets in a plane, displacing portions of said conductors relative to the normal plane thereof and in such a manner that the undisplaced portions of conductors of the same set occur at positions separated longitudinally of the plane 100 of the conductors and the undisplaced portions of corresponding conductors of different sets occur at the same position transversely of the plane of the conductors, inserting insulating strips between said conductors, and securing the structure thus formed to a mounting plate.

95

In witness whereof, I hereunto subscribe by name this 30th day of July A. D., 1917.

JOHN NEWBERRY REYNOLDS.
